UNITED STATES PATENT OFFICE.

WALTER ROCKWELL CRIPPEN, OF PELHAM, NEW YORK.

PHONOGRAPH ATTACHMENT.

1,377,186.

Specification of Letters Patent. Patented May 10, 1921.

Application filed February 26, 1920. Serial No. 361,550.

To all whom it may concern:

Be it known that I, WALTER R. CRIPPEN, a citizen of the United States of America, residing at Pelham, Westchester county, 5 New York, have invented a new and useful Phonograph Attachment, of which the following is a specification.

My invention relates particularly to an attachment for a phonograph of the disk record type.

The object is to provide a simple and inexpensive device which may be used to raise one edge of a record from the turn-table so as to facilitate its removal.

Another object is to provide a device of this character which can be readily attached to or detached from any ordinary disk type phonograph.

In its preferred form the invention comprises a thin flexible strip adapted to fit over 20 the spindle and lie flat across the top of the turn-table. Preferably it is of metal, and has one or more ends extending beyond the edge of the table. I also prefer to slot the 25 strip longitudinally so as to provide yielding jaws for engaging the spindle.

Figure 1 is a plan view of the turn-table with one form of device embodying my invention and showing a record in place.

Fig. 2 is a side view of the same but showing the record in section and tilted by means of the lifter.

Fig. 3 is a plan view of one form of attachment.

Fig. 4 is a plan view of a modified form of device having a single lifting arm.

The turn-table 5 has the usual rounded or tapered topped spindle 6, and is adapted to support a record 7 in the usual manner.

The lifter 8 has an opening 9 adapted to receive the spindle 6. This opening may be larger than the spindle, in which event, the lifter may be readily attached and removed. I prefer to provide a longitudinal slot 10 extending outwardly from the opening 9, and to make the opening slightly smaller in diameter than the spindle. This provides in effect jaws 11-11 adapted to yieldingly grasp the sides of the spindle and prevent accidental disengagement. By mak-

ing the lifter of very thin material, it will lie flat beneath the record without appreciably tilting the record, especially when the table is covered with felt or other similar material such as is customarily employed on 55 phonograph turn-tables.

It will be seen that this device may be applied to any standard type of disk machine without in any way modifying the turn-table. It will also be seen that it may 60 be applied by anyone without the use of any tools or appliances.

Obviously, the lifter may be finished in any suitable manner and ornamented if desired.

It will also be obvious that the device may be sold attached to a phonograph or as a separate article of manufacture by itself.

The form shown in Figs. 1 to 3 has two arms or ends extending in opposite directions from the center. The form shown in Fig. 4 has but one arm extending beyond one edge of the table. Obviously, the two armed device is more convenient as it provides two points for operating the lifter. Additional 70 arms might be provided, but, of course, this would increase the cost and make the device more cumbersome. It should be understood however that I consider the broader claims 75 to cover a device of this character having 80 any number of arms.

I claim:

1. As an article of manufacture, a lifter for a phonograph record, comprising, a thin flexible strip having an opening of a size 85 adapted to receive a phonograph turn-table spindle and adapted to lie flat upon and be carried by the phonograph turntable with one end of said strip projecting beyond the edge of said table. 90

2. In a phonograph, a record lifter, comprising, a turntable adapted to receive a record, a thin record lifting strip adapted to lie flat upon and be carried by the turntable, means for securing said strip adjacent to the 95 axis of said turntable, the outer end of said strip projecting beyond the edge of the turntable for accessibility.

WALTER ROCKWELL CRIPPEN.
